UNITED STATES PATENT OFFICE.

ADOLPH W. MACHLET, OF ELIZABETH, NEW JERSEY.

BARRE-PREVENTING MEANS FOR LOOMS.

Application filed April 13, 1925. Serial No. 22,773.

To all whom it may concern:

Be it known that I, ADOLPH W. MACHLET, a citizen of the United States, residing in Elizabeth, in the county of Union and State of New Jersey, have invented certain new and useful Improvements in Barre-Preventing Means for Looms, of which the following is a specification.

This invention relates to the brakes and 10 brake-drums which are used in looms for alternately restraining and releasing the warp-threads; the drum paying off the warp at intervals.

It is customary to employ a brake in the 15 form of a friction clutch connected to the drum or spool which carries warp-threads. The brake comes into play automatically when the warp opens and closes. The friction clutch usually consists of windings of 20 cord or rope, these windings being usually carried around the drum itself. The rope is usually weighted and otherwise controlled in a manner to relieve the longitudinal tension of the brake-rope at intervals, for the 25 purpose of loosening the coils thereof on the drum, thereby releasing the drum, as required during the weaving operation; this release usually occurring once for every throw of the weaving shuttle.

30 In weaving a narrow silk ribbon, two windings or bights of the rope may be taken around the brake-drum, a weight being attached to one end of the rope or strap. For a wider ribbon there may be three windings, 35 and so on, suitable means being provided for controlling the ropes, automatically tensioning and detensioning the same. When the brake or clutch is loose, it is only desired to give a slack; but the automatic device 40 must reliably let the brake loose, so that the warp can open. The rope-brake should loosen just for a touch; and the warp must open or spread up and down, and then the break must grip again, because the warp has 45 to be wound. The ropes are solely for putting a brake on the drum and for releasing it; they hold the drum while the bobbin is traveling between the separated sheets of warp-threads, and then the drum is released, 50 so as to permit the transposition of the warp-threads preparatory to another operation of the shuttle.

Trouble is experienced because the brake cannot be depended upon to release properly 55 in every instance. It should release the drum when the warp is pulled up. This is

the time when the bar comes in to press the thread up against the preceding threads. If the release is not properly effected, a miss will be made, and this miss may last through 60 one to four shuttle operations, with the result that the spacing of the warp-threads is rendered uneven, or what is known in the trade as a "barre" is produced. The failure of the brake to effect a release, subjects the 65 warp to a strain. The warp may be strained sufficiently to overcome the friction of the brake. When the brake does finally let go, it exceeds its normal action, and that results in unevenness or irregularity of weaving. 70 This trouble is serious, inasmuch as silk or other fine products containing these barres or barre-marks have to be sold at one-half or even a smaller fraction of the selling price of perfect goods, although the cost to the 75 manufacturer is the same.

The drum is made of cast-iron, which is smoothed, but it is exposed to dampness and rust, and it has been proposed to effect a 80 cure for the sticking of the brake by improving the finish of the drum, to make it smooth and less liable to rust.

In overcoming this fault of improper release of the brake, I have discarded the theory that the fault of sticking is due to 85 adhesion of the drum to the rope-coils, and have devised means for preventing sidewise sticking or seizing of the rope-coils upon one another. In tautening the rope, there 90 is a slight endwise movement thereof in each coil relatively to the next; and at the releasing operation I have prevented the seizing of one coil upon another which has heretofore prevented the endwise slackening 95 travel of the rope, so that the same has heretofore remained tightly clenched upon the drum, although its dangling end has been slack. The drum is usually of large diameter, and the length of rope required to wind 100 two or more times around the same is considerable, and throughout its length there is some relative movement of the rope at each tightening operation, and relative slackening of the rope at each releasing operation; and the face contact through such 105 a long length of rope is too extensive to be easily overcome, wherefore the brake has remained in its tautened condition, whereas according to my invention the brake releases 110 instantly.

Other features and advantages will hereinafter appear.

In the accompanying drawings or diagrams,

Figure 1 is a front elevation of the work-controlling brake-drum of a loom, showing the present improvements placed thereon.

Figure 2 is a side elevation of the drum, showing the relative positions of the parts seen at Figure 1.

Figure 3 is a perspective view of a helical spacing collar, forming a new article of manufacture and ready to place upon the drum.

According to the present invention required prompt slackening of the windings of rope 10 is provided for by means of a novel device which renders impossible the seizing of one coil by the next, even to the slightest degree. This is effected by means of a collar which is placed loosely upon drum 11, and which has the form of a helix or worm 12 which winds around the drum between the coils 13 of rope, thus separating said coils from one another. Preferably the whorls A of the helix alternate with the windings of whorls 13 of the rope, so that each coil 13 is always separate from the next, and cannot possibly catch thereon; although the invention may be carried out in a variety of other ways.

The coil-separating collar may be in the form of a smooth strip of steel or other metal. For example, it may be in the form of a flat wire three-quarters or seven-eighths of an inch wide, and one-eighth of an inch thick. This may be wound up edge-wise to make a helix which is placed loosely in the form of a collar upon the drum 11, or upon each of the brake-drums 14 fixed upon the ends of the warp-drum or spool 11.

The whorls A of this helical collar are spaced each from the next, thereby to form, with the drum 14, channels or beds for the coils 13 of rope, said rope-coils being thus spaced by the whorls of the collar. The novel separating collar prevents the coils of rope from seizing or chafing upon one another, and thereby insures prompt releasing action of the brake, and hence avoids great losses heretofore suffered through faulty weaving.

Each brake-drum 14 has flanges 15 which confine the rope-coils, and the novel collar may be placed upon said drum between said flanges. The collar may be gradually worked or wormed, point first, over the drum-flanges, and into position upon the drum, by a sort of cork-screwing action, the material of the collar being springy and yielding a little to permit it to be forced over the flange 15 and onto the brake-drum, whereby the novel separator may be placed in position without taking down any part of the loom. Said flanges 15 will then confine the spacing collar, as well as the rope-windings. As many coils of rope may be

provided for as required, by making a corresponding number of whorls A in the collar; and such collar will be useful also for any smaller number of coils of rope.

In order to prevent the spacing collar from turning around with the drum, said collar may be provided at one end with a pendent extension 16, having an eye 17 through which the pendent rope is passed, said extension forming an arm which enables the pendent rope to retain the collar in one place upon the drum, or prevents it from turning idly around the drum, which revolves when released from the brake.

This extension 16 may stand at any angle. Sometimes one of the ropes goes over an idler; and the restraining eye 17 may be provided for in a variety of ways. This eye is not needed on both ends of the spacing collar.

The helical separators, Figure 1, form a pair, preferably right and left.

The invention has great value in making the finest grade of cloth. It can be used for cotton as well as silk, especially where an imitation of silk is produced from cotton.

Variations may be resorted to within the scope of the invention, and portions of the improvements may be used without others.

Having thus described my invention, I claim:

1. In a loom having a brake-drum controlling the warp-threads, and a rope coiled repeatedly around the drum and provided with releasable tension means, a device preventing the rope coils from chafing one another, said device in the form of a helix loose upon said drum and separating the coils of rope one from another.

2. In a loom having a brake-drum controlling the warp-threads, and a rope coiled repeatedly around the drum and provided with releasable tensioning means, a device preventing the rope coils from chafing one another, said device in the form of a helix loose upon said drum and separating the coils of rope one from another, and means preventing the helix from revolving with the drum.

3. In a loom having a brake-drum controlling the warp-threads, and a rope coiled repeatedly around the drum and provided with releasable tensioning means, a device preventing the rope coils from chafing one another, said device in the form of a helix loose upon said drum and separating the coils of rope one from another, said helix having an extension engaged by one end of the rope, preventing the helix from turning around the drum.

4. In a loom having a brake-drum controlling the warp-threads, a rope coiled repeatedly around the drum in contact therewith and provided with releasable tensioning means, and means loose upon said drum and

preventing the rope coils where in contact with the drum from seizing one another.

5. A pair of helical rope-separating collars loosely mounted upon the warp-controlling brake-drum of a loom, and means for preventing the collars from revolving.

6. A pair of helical rope-separating collars loosely mounted upon the warp-controlling brake-drum of a loom, and means for preventing the collars from revolving, said collars being formed with right and left helices.

7. A pair of helical rope-separating collars loosely mounted upon the warp-controlling brake-drum of a loom, and means for preventing the collars from revolving, said collars being formed with right and left helices, and each having at one end an eye through which the rope passes, and by which 20 the collar is prevented from turning with the drum.

8. The combination with the warp-controlling brake-drum of a loom, of guides for the coils of brake rope upon the drum, comprising helical devices separating the coils and carried by the drum but non-rotative therewith.

9. The combination with the warp-controlling brake-drum of a loom, of guides for the 30 coils of brake rope upon the drum, comprising helical devices separating the coils, and means to support said coils without permitting them to revolve with the drum.

10. A helical device permanently inserted

between the coils of rope upon a brake-drum 35 to separate the same, and means preventing said device from revolving with the drum.

11. A strip of metal formed into a helix having separated whorls and confined between the flanges of the warp-controlling 40 brake-drum of a loom, means being provided for restraining the helix from revolving with the drum.

12. As a new article of manufacture, a loose helix forming a collar having its 45 whorls separated to form spaces for coils of rope upon the warp-controlling brake-drum of a loom, and having means whereby the collar may be restrained against rotation.

13. As a new article of manufacture, a loose helix forming a collar having its whorls separated to form spaces for coils 50 of rope upon the warp-controlling brake-drum of a loom, and having means whereby the collar may be restrained against rotation, said restraining means in the form of an eye projecting from one end of the collar.

14. As a new article of manufacture, a loose helix forming a collar having its 60 whorls separated to form spaces for coils of rope upon the warp-controlling brake-drum of a loom, said helix formed of a springy metal capable of being wormed into position between the flanges of the brake-drum while the same remains in place upon the loom.

ADOLPH W. MACHLET.
